UNITED STATES PATENT OFFICE.

CHARLES FEARON AND WILLIAM E. BRADLEY, OF PHILADELPHIA,
PENNSYLVANIA.

SWITCH-SIGNALING DEVICE.

SPECIFICATION forming part of Letters Patent No. 635,130, dated October 17, 1899.

Application filed April 9, 1898. Serial No. 677,007. (No model.)

To all whom it may concern:

Be it known that we, CHARLES FEARON and WILLIAM E. BRADLEY, citizens of the United States of America, residing in the city and county of Philadelphia, in the State of Pennsylvania, have invented a certain new and useful Improvement in Switch-Signaling Devices, of which the following is a true and exact description, reference being had to the accompanying drawings, which form a part thereof.

Our invention relates to railroad switch-signaling devices, and has for its object to provide an electric signal or signals so connected with the movable rail of a switch as to be actuated thereby and to indicate at proper places the condition of the switch; and particularly our object is to provide apparatus for effecting these purposes at once simple and at the same time constructed so as to be free from liability to injury in the ordinary exigencies of use.

The nature of our improvements will be best understood as described in connection with the drawings, in which they are illustrated, and in which—

Figure 1 is a plan view of a switch, indicating a portion of our apparatus as used in connection therewith. Fig. 2 is a cross-sectional view through the casing, which, with its attachments, forms an important feature of our invention, taken on the section-line 1 1 of Fig. 3. Fig. 3 is a vertical cross-section through the casing, taken as on the section-line 2 2 of Fig. 2; and Fig. 4 is a diagrammatic view showing the arrangement and connection of signals and signal-actuating devices which we prefer to employ.

A and A' indicate the two fixed rails of the main track and a siding. B is the second rail of the main track, having a movable switch-point b; and B² is the second rail of the switch having the movable pin b'.

C is a base-plate or box secured permanently below one of the movable switch-points, as b', and provided with bearings, as indicated at C' C', to support the movable casing, which is indicated at D, d indicating a removable face to the casing.

D' and D² are trunnions extending from the casing, one portion being made in the form

of a tube, as indicated, opening at one end and also through a lateral opening d² into the center of the casing D with a concavely-curved top face D³, in close proximity to which rests the movable point b' of the switch, the arrangement being such that as the switch-point is moved to one side or the other it will cause the casing D to oscillate on its bearings, while at the same time in each position of the switch-point the casing is in a definitely-determined position.

The plan shown for communicating motion from the switch-point to the casing is a simple one and well adapted for the purpose; but it must be understood that we do not limit ourselves to the use of any particular device for communicating an oscillating motion to the casing corresponding to the reciprocating motion of the switch-point.

E indicates a stuffing-box.

F is a tube made of some electrical conducting metal and secured to the end of the casing D, as shown. Preferably it is made with a longitudinal curve, as indicated, and it is provided with end caps, through which project conducting line-terminals G and G', insulated from electrical contact with the metal of the tube.

H indicates a switch for making contact between the tube and the electrical conducting-terminals at its ends, and in our preferred construction, as shown, it consists of a globule of mercury, which, coming in contact with other terminals, places it in electrical connection with the body of the tube and through it with the casing. It will be understood that in substance this device consists of two line-terminals secured to but out of electrical contact with the body of the casing and used in combination with a gravity-switch so suspended in the casing that as said casing oscillates from one side to the other it will at determined points in the oscillation come into contact with the terminals and place them in electrical connection with the casing and through it with the ground. The use, therefore, of the conducting-tube as a device for supporting the gravity-switch is not essential, although for many reasons we prefer and recommend its use.

I and I' indicate circuit-wires connecting

with the terminals G and G', and at their other ends connecting with a single line-wire I², of which they form branches, and which, as shown, passes through a battery K to ground, (indicated at J.)

I³ I⁴ indicate a circuit connected with the battery K, the line-wire I³ terminating in a switch-plate M', while the line-wire I⁴ terminates in a switch M, normally held in contact with the plate M' by a resilient force, such as spring M².

L indicates the electromagnet situated in the line-wire I² and so placed as to act upon the switch M and draw it out of contact with the switch-plate M'.

N is a signal—as indicated, a call-bell in the circuit I³ I⁴.

O and O' are electromagnets placed opposite to each other in the branch lines I and I' and arranged so as to act upon an armature P' of an indicating-finger P.

At f I have indicated what is at the same time a modification of the gravity-switch already described and also an advisable addition to the signaling system as a whole. It consists of a tube like the tube F, though, as shown, it is straight and not curved, and is provided with a terminal, as indicated at g, only at one end, h indicating the globule of mercury constituting the gravity-switch and i indicating the line circuit-wire extending from the terminal g through a battery k and signal n to a ground j. It is obvious that the single terminal-switch, such as indicated at f, will connect the line-wire to ground when the casing is moved in one direction and break this connection without making another connection when the movement of the casing is reversed.

The operation of the device and system illustrated and above described is as follows: The switch-point b' being at one of its extreme and operative positions the casing D is tilted, with the result of bringing the gravity-switch H into contact with the terminal G', thus closing the circuit from ground through casing, metal-tube switch-globule H, terminal G', and lines I and I² to ground J. The energizing of the magnet O causes the indicator P to be drawn toward it, as shown, and the energizing of the magnet L draws and holds the switch M out of contact with the plate M'. A movement of the switch-point to the intermediate position shown in Fig. 2 causes the gravity-switch globule H to assume a position between and out of contact with both terminals G and G', so that no current passes through the circuit connected with the battery K, and therefore the indicator P will assume a forward position midway between the magnets O and O', while the magnet L, not being energized, will release its hold on the switch M, permitting it to close and to close the circuit I³ I⁴, whereupon the bell or other circuit (indicated at N) will be actuated, indicating that the switch has not been properly set. Again, if the move-

ment of the switch has been complete it will tilt the casing D in the other direction from that indicated in Fig. 4, bringing the globule H into contact with the terminal G and closing the circuit through the branch line I' and line I², with the result of attracting the indicator P toward the right, while at the same time the energizing of the magnet L will open the circuit I³ I⁴.

Where it is only desired to indicate whether the switch is in one certain position or not or where it is desired to provide this indication in addition to those provided for in the above-described device, the single terminal-switch (indicated at F) can be conveniently used, its operation being to actuate the signal N in one position and not in any other position of the switch or casing.

Having now described our invention, what we claim as new, and desire to secure by Letters Patent, is—

1. In an electrical switch-signaling device, a casing as D, having a concave upper face D³ and oscillatable in proper bearings, in combination with one or more line-terminals situated in and movable with said casing, a gravity-switch suspended in the casing and adapted to make and break contact with the terminal or terminals as the casing oscillates from one position to the other, and a switch-rail situated immediately over and in operative position with respect to the face D³ of the casing and so as to turn the casing as it is moved and thus shift the terminals with reference to the gravity-switch.

2. In an electrical switch-signaling device, a casing as D, having a concave upper face D³ and oscillatable in proper bearings, in combination with a tube of copper or other conducting material having a line terminal or terminals at its end or ends projecting into, but insulated from, the tube, a globule of mercury contained in the tube and adapted when at the end or ends thereof to electrically connect the tube and terminal, and a switch-rail situated immediately over and in operative position with respect to the face D³ of the casing and so as to turn the casing as it is moved and thus shift the terminals with reference to the gravity-switch.

3. In an electrical switch-signaling device, the combination with a battery, a circuit-wire as I² connected therewith and in turn connected to two branch wires, as I I', of an indicator, as P, a magnet, as O O', in each branch wire arranged to actuate the indicator in different directions, a signal-circuit as I³ I⁴, a switch in said circuit and resilient means, as a spring, acting to close said circuit, an electromagnet in the line-wire I² arranged to act upon said switch, and hold it open when energized, a switch arranged to move between the terminals of the branch wires I I' and to close the circuit from the battery when in contact with either of them, a switch-rail and means for moving the electrical switch in accordance with the move-

ments of the switch-rail, substantially as specified, and so as to show the position of the switch by the indicator P and to close the signal-circuit $I^3 I^4$ when the switch-rail is not 5 fully thrown to its operative or non-operative positions.

4. In an electrical switch-signaling device, a casing, as D, oscillated on proper bearings in combination with two line-terminals situated in and moving with the casing, a gravity-switch suspended in the casing between said terminals and arranged to make contact with one or the other in the extreme positions of the casing, a third line-terminal also situated 10 in and moving with the casing, a gravity-

switch situated in the casing and arranged to make contact with the terminal in one position thereof, signaling devices connected with the terminal, a switch-rail, and means for communicating motion from the rail to 15 the casing as specified and so as to shift the terminals with reference to the gravity-switch.
